BEARING CONSTRUCTION FOR
CONTINUOUS CENTRIFUGEFred P. Gooch, Media, Pa., assignor to The
Sharples Corporation, a corporation of Dela-
wareOriginal application January 15, 1947, Serial No.
722,124. Divided and this application Decem-
ber 24, 1952, Serial No. 327,763

4 Claims. (Cl. 233—7)

1

This application is a division of my co-pending application Serial No. 722,124, filed January 15, 1947. The invention pertains to an improvement in centrifugal machines designed for separation of liquid from solids. More particularly, it is concerned with a machine of this type in which a mixture of liquids and solids is continuously fed to the rotor, liquid separated from the solids by rotation of the rotor during such continuous feed, and the liquid and solid fractions separately discharged from the rotor.

Features of improvement involved in the present invention include improved means for preventing leakage of liquid under treatment to bearing surfaces and preventing leakage of lubricant from bearing surfaces into the liquid under treatment.

The invention will be described in connection with a machine which, in its preferred form, includes rotating impeller means for impelling solids longitudinally of the rotor to a discharge zone for said solids, and this impeller means is driven at a speed slightly different from the speed of the rotor in order to effect the desired longitudinal movement of the solids.

Further features and advantages of the invention, and the manner in which they have been attained, will be evident from a reading of the following detailed description in the light of the attached drawing, in which,

Figure 1 is an elevation partly in section along the center axis of a machine in which the invention is embodied;

Figure 2 is a transverse vertical section on the line 2—2 of Figure 1; and

Figure 3 is a transverse vertical section on the line 3—3 of Figure 1.

In the drawings, the machine illustrated includes a feed conduit 10 controlled by a valve 11 for delivery of a mixture of liquid and solids into the hollow centrifugal rotor designated generally 13. The solids are impelled longitudinally of the rotor by a rotating scroll 14 of the nature of an impeller which causes these solids to move toward the right-hand end of the rotor as illustrated in Figure 1, at which end the rotor and impeller are driven by means of a pulley 15. The driving connection between the two includes a gear box 16 at the opposite end of the machine interconnecting the drives of the rotor and impeller and causing differential rotation of these two elements. A housing 20 surrounds the rotor, the housing, rotor and associated parts being secured to a frame 21.

Slurry fed to the machine through feed con-

2

duit 10 passes through the valve 11 into conduit 22, which directs the slurry to a delivery zone 12 in the central portion of the rotor, where the slurry is discharged through a series of rotating blades 23 into the conical bowl 24 of rotor 13. Here the mixture undergoes centrifugation which deposits the heavier solids on the inner wall of bowl 24, the liquid flowing through liquid discharge ports 25 in end piece 26 of the rotor. Meanwhile, the solids are moved along the inner wall of bowl 24 by the impeller 14 and are discharged through solids-discharge ports 27 into a receiver in the form of a chute 19.

A portion of the solids may be discharged 15 against the curviform collecting shield 28 in the upper portion of receiver 19. Solids which impinge against this surface are removed therefrom by a pair of rotating members 29, 30 passing closely adjacent to the surface of shield 28 as described and claimed in co-pending application Serial No. 328,699, filed December 30, 1952. Although these members may be rotated independently of the rotor, being supported in such case on bearings mounted on the rotor or on any 25 suitable supporting member, more conveniently they may be formed as shown; i. e., as opposed curved rotating members or surfaces attached to the rotor on opposite sides of discharge port 27. These rotating members assist in conveying 30 solids around the axis of the rotor and depositing them in receiver 19.

The rotor 13 is driven by means of pulley 15 attached to an end piece 31 which is integral with bowl 24 of the rotor. Bearings 32 and 33 mounted at opposite ends of frame 21 permit rotation of the rotor about its axis. The end piece 26 at the large end of the rotor is attached to bowl 24 of the rotor for rotation therewith. In turn, casing 34 of gear box 16 is connected to end piece 26. Impeller 14 is driven from shaft 35, which is rotated at a speed differing from that of the casing 34.

The impeller may be composed of sections such as 36, 37, 38 and 39, each connected to the other for rotation as a unit. The curviform solids-conveying surface 40 may be connected to one or more of these sections for rotation at an angular speed differing from the angular speed of rotor 13. The impeller is supported by means of 45 bearings such as 41 and 42 from end pieces 26 and 31. A thrust bearing 43 may be provided to prevent longitudinal movement with respect to the rotor.

In accordance with this invention seal 44 be-
50 tween section 36 of the impeller and end piece

26 of the rotor and the seal 45 between the hollow hub section 39 and end piece 31 serve to prevent passage of materials being subjected to centrifugation into the bearings 41 and 42 and to prevent contamination of these materials by 5 lubricant from the bearings.

The bearings 41 and 42 may be lubricated from an external source through the channels 46 and 47. Excess lubricant passing through the bearings will be thrown into the areas 48 and 10 49 adjacent to the seals 44 and 45. Here the lubricant will serve to assist in sealing the bearings from material which may reach the seals from the zone of centrifugation in the rotor. When the levels of materials in the areas 48 and 15 49 rise towards the bearings 41 and 42, material is drawn off through the vents 50 and 51 before these levels reach the bearings. Preferably these vents discharge outside the bowl housing 20 in order to furnish an immediate warning of seal 20 difficulty with the discharge of any materials which may build up in the chambers 48 and 49.

Although the foregoing discussion has been limited to a centrifugal machine in which the rotor is directly driven from a source of power and the impeller is driven through suitable gearing connected to the rotor, this arrangement of drive is not to be regarded as a limitation of the invention. It will be obvious that the impeller 25 may be directly driven from the source of power, that the gear box may be driven from the impeller, and that the rotor may be revolved at a speed differing from that of the impeller through the medium of the gear box. Another suitable method of drive may be to connect a section of the 30 gear box directly to a source of power.

The difference in speed of rotation of the impeller member 14 and the rotor 13 obtained through the gear box 16 are achieved by means well known in the art, many different power 40 transmission mechanisms having been disclosed for this purpose. As illustrated this includes a planetary system having a pinion 54 the rotation of which is restricted by a lever 72 and connecting link 73 attached to control mechanism 45 forming no part of this invention.

The rate of feed of slurry into the rotor of the centrifugal is controlled by the valve 11 acting in the feed conduit 10. As illustrated gate 50 70 and the body 71 of this valve are so formed by use of curved surfaces against the flow line of the slurry that solids suspended in the liquid portion of the slurry which may impinge upon surfaces of the valve or valve body cannot remain thereon because the angles of the surfaces to the lines of flow are greater than the dynamic angle of repose of the solids.

A valve motor 91 is illustrated in Figure 1 as having a piston 96 which acts under fluid pressure within chamber 97 against the reaction of the spring 98, fluid pressure being admitted through line 99. Valve gate 70 is shown attached to piston 96 by means of a piston rod 99; thus, the position of the piston 96 determines the aperture of the valve 11. Any other means for controlling valve 11 may be provided.

The extent of the centrifugal operation to which materials in the feed slurry are subjected is controlled by adjusting the axial position of the slurry feed means so that the location of the zone of discharge of slurry from the feed conduit may be axially moved as described and claimed in my above-mentioned parent application. One method of doing this is by changing the position 70 of the conduit 22 which relocates the discharge 75

port 100 in which the slurry passes into the discharge zone 12. Conduit 22 may be positioned by means of a lock screw 101 or any similar positioning device so that the discharge port 100 may be located in any desired relationship with the deflectors 102. A plurality of openings in the conduit 22, each individually controlled, or relocation of the discharge lip of the port 100 may be used to accomplish this same purpose.

Slurry is fed to the machine through a zone 103 of the impeller when the conduit 22 is at the right as shown in Figure 1. When the conduit 22 is at the left instead of at the right as shown in Figure 1, the feed slurry passes into the rotor through a zone 104 of the impeller. This zone 104 is more remote from the solids-discharge port 27 than the zone 103 and therefore solid materials in the slurry are subjected to centrifugation for a longer period of time if the slurry is fed through the zone 104 than if the slurry is fed through the zone 103. The deflectors 102 serve to direct the slurry selectively or in any desired relative proportion into the zones 103 and 104. Blades 23 serve to accelerate the movement of the slurry as it passes radially through the impeller hub into the hollow body of the rotor.

The rotor cover 23 is formed in sections to permit rapid opening and inspection of the rotor and discharge conduits. This is accomplished by clamping means such as the swivelled studs 105 which are normally held in place by the wing nuts 106. To prevent discharge of materials thrown from the rotor ports under centrifugal force, the baffle 107 which may be integral with or attached to an upper section 108 of the rotor cover overlaps lower section 109 in the direction of rotation of the rotor 13. On the other side of the rotor a baffle 110 integral with or attached to the lower section 109 of the rotor housing overlaps the upper section 108 in the direction of rotation of the rotor. The upper section of the rotor housing 108 may be supported from the lower section 109 by means of the flanges 111 and 112 on the upper and lower sections respectively.

The baffles 107 and 110 prevent leakage of liquid and solid materials discharged from the bowl through ports 25 and 27 respectively to the area adjacent to the machine. The discharge of liquid is confined to the conduit 113 and the discharge of solids to the conduit 114 which have appropriate connections for delivery of separated materials into receiving vessels not a part of the machine. Use of these baffles permits the employment of quick locking features such as the swivel studs described to fasten the upper section of the rotor housing to the lower section. Gaskets between the sections of the housing may be dispensed with because of this baffling. These two elements, quick fasteners and the absence of a gasket, greatly facilitate removal of a section of the rotor housing whenever it is desirable or necessary to inspect the rotor and the discharge conduits for liquid and solid materials.

Various modifications are possible within the scope of the invention and I do not therefore wish to be limited except by the scope of the following claims.

I claim:

1. A centrifugal separator having a rotor, a member within said rotor mounted for rotation about the axis of rotation of said rotor, a space for centrifugal separation between said member and the inner periphery of said rotor, bearings

for said member at opposite ends thereof, a seal associated with each said bearing for isolating said bearing from said space for centrifugal separation, said seal being at a greater radial distance from said axis than said bearing, a vent positioned between said seal and said bearing at a radial distance from said axis between that of said seal and that of said bearing, and means for introducing lubricant into said bearing on the opposite side thereof from said seal.

2. A centrifugal separator having a rotor, a member within said rotor mounted for rotation about the axis of rotation of said rotor, a space for centrifugal separation between said member and the inner periphery of said rotor, bearings for said member at opposite ends thereof, a seal associated with each said bearing for isolating said bearing from said space for centrifugal separation, said seal being at a greater radial distance from said axis than said bearing, and a vent positioned between said seal and said bearing at a radial distance from said axis between that of said seal and that of said bearing.

3. A centrifugal separator having a rotor, a member within said rotor mounted for relative rotation therein, a space for centrifugal separation between said member and the inner periphery of said rotor, a bearing for said member, a seal associated with said bearing for isolating said bearing from said space for centrifugal separation, said seal being at a greater radial distance from the axis of rotation of said rotor than said bearing, a vent positioned between said seal and said bearing at a radial distance from said axis between that of said seal and that of said bearing, and means for introducing lubricant into said bearing on the opposite side thereof from said seal.

4. A centrifugal separator having a rotor, a member within said rotor mounted for relative rotation therein, a space for centrifugal separation between said member and the inner periphery of said rotor, a bearing for said member, a seal associated with said bearing for isolating said bearing from said space for centrifugal separation, said seal being at a greater radial

distance from the axis of rotation of said rotor than said bearing, and a vent positioned between said seal and said bearing at a radial distance from said axis between that of said seal and that of said bearing.
